UNITED STATES PATENT OFFICE.

THOMAS B. DRAPER, OF TORONTO, ONTARIO, CANADA.

FOLDING FURNITURE.

Application filed September 7, 1920. Serial No. 408,657.

To all whom it may concern:

Be it known that I, THOMAS B. DRAPER, a subject of the King of England, residing at Toronto, in the county of York, Province 5 of Ontario, Dominion of Canada, have invented certain new and useful Improvements in Folding Furniture, of which the following is a specification, reference being had thereto in the accompanying drawings.

10 This invention relates to folding furniture and more particularly to a settee, couch, sofa, or lounge that may be converted into a full width double bed having a spring and mattress all ready for bed clothes.

15 My invention aims to provide a piece of furniture which is susceptible to any desired exterior finish, for instance, along the lines of mission furniture, and my invention possesses the following characteristics:

20 First, the lounge, as it will be hereinafter termed, has its seat and back cushions arranged so as to be distended to form a bed structure having a top spring with a novel mattress thereon, and the arrangement of the 25 spring and mattress is such that both of these articles are folded and concealed within the lounge structure, which also affords sufficient space for bed clothes.

Second, the lounge has arm rest supports 30 and arm rests with the arm rest supports arranged to afford intermediate bed feet and the arm rests disposed to afford end bed feet, so that the bed structure will be safely supported and present a neat and attractive 35 appearance.

Third, the lounge is provided with counterbalancing devices for the movable seat cushion and back cushion thereof, said devices preventing any sudden action of the 40 cushions when being distended for a bed structure, and the same devices will facilitate raising and folding the foot portion of the bed structure, so that a woman may easily manipulate the piece of furniture.

45 Fourth, the folding piece of furniture is further characterized by an automatic locking device which prevents displacement or any tendency of folded parts to open, and another locking device prevents a taut bed 50 spring from raising distended parts of the bed structure.

The above are a few of the main features of my invention and others will appear as the nature of my invention is better understood.

55 stood.

Reference will now be had to the drawings, wherein—

Figure 1 is a longitudinal sectional view of a piece of furniture unfolded or distended to provide a bed structure, and in dot and dash lines portions of the structure are shown in shifted position;

Fig. 2 is a plan of the same partly broken away;

Fig. 3 is a vertical cross sectional view of the lounge showing the folded bed spring and mattress therein by dot and dash lines;

Fig. 4 is a longitudinal sectional view of the lounge taken on the line IV—IV of Fig. 3 and partly broken away;

Fig. 5 is a cross sectional view of a portion of the lounge partly unfolded or distended, and

Fig. 6 is an end view of the lounge partly broken away and partly in section.

The lounge comprises a back frame having end legs 1 connected by a top rail 2 and a bottom rail 3 and said rails are connected by a plurality of vertically disposed slats 4. Connected to the lower portions of the end legs 1 are side frames 5 having front end legs 6 connected by a front rail 7 and this rail is connected to the bottom rail 3 by a plurality of slats 8, the slats 8 and 4 cooperating with the side frames 5 in forming somewhat of an oblong box structure or housing in which may be housed a flexible or foldable bed spring 9, a mattress 10, and such bed clothes, pillows, etc., that may be used on a bed structure.

The inner sides of the legs 6, adjacent the upper ends thereof, are provided with pintles or pivot members 11 for seat end frames 12 and these seat end frames and the legs 6 may have suitable bearings or wear plates 13 for the pivot members 11. The seat end frames 12 are connected by longitudinal seat rails 14 and 15 supporting a conventional form of spring seat cushion 16. The seat end frames 12 are also provided with arm rest supports 17 having dowel pins 18 and said arm rest supports constitute intermediate bed feet when the seat cushion is unfolded or distended to form the intermediate portion of a bed structure. The end frames 12 have ledges 12^a to rest on the upper edge of the front rail 7 and thus release the pintles 11 of any great weight when the cushion 16 is in use as a lounge.

Connected to the seat end frames 12, ad-

adjacent the ledges 12^a, are counterbalancing devices 19 including links 19^a and coiled retractile springs, and said counterbalancing devices are connected to the end legs 1 of the lounge back frame, at the inner sides thereof, so that said devices will extend along the inner sides of the frames 5, as best shown in Figs. 1 and 2. The links 19^a of the counterbalancing devices extend across the seat rail 15 and bear thereon when the seat cushion is unfolded or distended and said devices constantly aim to raise the seat portion from an unfolded position to a folded position, and it is only necessary to slightly raise the unfolded seat cushion, as shown in Fig. 1, in order to have the devices 19 co-operate in assisting further movement of the seat cushion. It is obvious that these devices will also cooperate in preventing a sudden and jarring opening movement of the seat cushion, as the same is unfolded and placed in an active position as the intermediate portion of a bed structure. To prevent the counterbalancing devices from raising the distended seat cushion, locking devices 20 connect the seat end frames 12 to the side frames 5, each locking device comprising toggle or rule joint links which, when in alignment, as shown in Fig. 1, prevent the seat end frames 12 from raising under the influence of the counterbalancing devices 19. The locking devices may be manually broken or shifted upwardly, as indicated by dot and dash lines in Fig. 1, to permit of the counterbalancing devices 19 assisting in folding or closing the seat cushion, and where said locking devices are connected to the end frames 12 there are side lugs 20^a which impinge against the links 19^a and forcibly lower said links into parallelism with the inner wall of the front rail 7, as best shown in Fig. 3. This places the links 19^a in such a position that considerable leverage is obtained for the springs when assisting in raising the seat cushion as said springs pull against the side lugs 20^a which are in a plane below the pintles 11 and must ride against the links 19^a until the seat cushion is well raised from the lounge frame, (see Fig. 5).
Connected to the seat end frames 12 by suitable hinges 21 or other pivotal means are back end frames 22 connected by rails 23 and 24 supporting a back cushion 25 and on the rail 24 is an angle bar 26 and a finishing rail or stop 27. The angle bar 26 cooperates with a tiltable angle bar 28 connecting the end legs 1 of the back frame in supporting the bed spring 9 and when the seat and back cushions are in unfolded or distended position, as shown in Fig. 1, the bed spring 9 is maintained taut and supports the mattress 10 in a manner as will be disclosed in a companion application, filed under even date.
At the outer sides of the back end frames

22 are side supports 29 for arm rests 30 and these arm rests serve as end bed feet in connection with the bed structure. The lower or rear faces of the arm rests 30 are grooved or provided with sockets 31 to receive the dowel pins 18 of the arm rest supports 17 when the bed structure is folded to provide a lounge. When so folding the bed structure the finishing rail or stop 27 abuts the top rail 2 of the back frame to limit the closing movement of the bed structure, and by reference to Fig. 3, it will be observed that the rail 27 protrudes above the rail 2 and can be easily gripped and pulled forwardly when distending or unfolding the lounge.

On the outer sides of the back end frames 22, adjacent the side supports 29 are angle keepers 32 adapted to engage under angle latches 33 on the inner sides of the end legs 1, as best shown in Figs. 1 and 6. The keepers 32 snap under the latches 33 and prevent any raising movement of the seat and back cushions until manually manipulated, at which time the forward movement of the back cushion removes the angle keepers 32 from under the angle latches 33, and then the back cushion can be elevated.

Thus far I have considered the mechanical construction of the lounge and now considering the operation of converting the lounge into a bed structure and vice versa, it is only necessary to grip the finishing rail 27 and pull the same forwardly when the back and seat cushions will be bodily raised, turning at the pintles 11, as shown in Fig. 5. As the seat cushion is swung over the pintles the back cushion opens forwardly, as shown in Fig. 1, and can be lowered until the arm rests engage the floor and serve as end bed feet. As pointed out in the beginning the counterbalancing devices 19 are brought into action to prevent a sudden lowering movement of the seat and back cushions. It is now necessary that the locking links 20 be manually straightened out and the bed structure is ready to be made up if the bed clothes are not attached to the mattress 10. By reference to Fig. 1 it will be observed that the bed spring 9 is supported free of the end frames 12 and 22 and some distance above the side frames 5, consequently the bed spring will possess the same degree of resiliency as an ordinary bed spring.

To fold the bed structure the back cushion is raised after the locking links 20 are broken upwardly and the breaking of these locking links permits of the counterbalancing devices 19 assisting in raising the seat cushion so that as the cushions are moved towards the back frame the angularly disposed edges of the end frames 22 may engage the angularly disposed edges of the end frames 12. The arm rests 30 will eventu-

ally engage the supports 17 and the finishing rail 27 engage the top rail 2. It is during this folding movement of the seat and back cushions that the spring 9 and the mattress 5 10 fold into the box like structure afforded by the back frame and the spring 9 will cause the angle rail 28 to tilt, as shown in Fig. 3, so as to prevent buckling of said spring.

10 Considering the lounge, as shown in Figs. 3 and 6, it is to be noted that the pintles 11 cooperate with the finishing rail 27 in supporting the seat and back cushions relative to the lounge frame and due to the relation 15 of the end frames 12 and 22 there can be no breaking down of these cushions due to any reasonable weight on the same.

Throughout the construction of the piece of furniture I may use angle brackets or 20 filler blocks, for instance, on the arm rest supports 17 to assist in supporting the arm rests 30, and at such other places where parts may be braced or made ornamental. It is practically impossible to detect that 25 the lounge may be converted into a bed, and the manner in which the piece of furniture is constructed materially reduces the weight of the same compared with folding furniture. The use of metal is reduced to a minimum 30 without sacrificing strength and rigidity and it is obvious that panels may be substituted for the slats 4 and 8 to protect the mattress and bed clothes from dust and dirt.

One embodiment of my invention has been 35 illustrated, but it is to be understood that the structural elements are susceptible to such changes as fall within the scope of the appended claims.

What I claim is:—

40 1. In foldable furniture, a lounge frame, a seat cushion pivotally connected thereto and adapted to be extended to provide intermediate bed feet, and a back cushion connected to said seat cushion and having arm 45 rests serving as end bed feet.

2. In foldable furniture, a lounge frame, a seat cushion, a back cushion, and means carried by both of said cushions adapted to cooperate in providing arms for said lounge 50 frame, said frame and cushions being articulated to be distended to form a bed structure

devoid of any side upright or arms above the plane of the sleeping surface of the structure.

3. A lounge comprising a frame, articulated cushions in said frame supported at the forward edge of said frame and at the upper edge thereof, arm rests carried by one of said cushions, and arm rest supports carried by the other of said cushions for the 55 arm rests of the first mentioned cushion.

4. A lounge adapted to be converted into a bed, comprising a frame, a seat cushion pivoted in said frame and having arm rest supports, a back cushion hinged to said 65 seat frame and having arm rests to engage the rest supports of said seat cushion and provide side arms for the lounge.

5. A lounge adapted to be converted into a bed having a head, intermediate and foot 70 portions, and side arms for the lounge, portions of said side arms being carried by the intermediate and foot bed portions to assist in holding said portions for the bed.

6. In a piece of folding furniture which 75 has a back frame and a seat cushion pivotally connected thereto and adapted to be raised and inverted, a locking device connecting said seat cushion and back frame, side lugs forming part of said locking device and in a plane below the pivots of said seat cushion when said seat cushion is in 80 said back frame, and counter balance devices for said seat cushion adapted to engage said side lugs and assist in raising said seat 85 cushion to be inverted.

7. In a piece of folding furniture which has a back frame and a cushion pivotally connected thereto and adapted to be raised and inverted, lugs carried by said cushion 90 normally below the plane of the pivots of said cushion and a counter balance device connecting said back frame and cushion and adapted to engage said lugs and assist in raising said cushion. 95

In testimony whereof I affix my signature in presence of two witnesses.

THOMAS B. DRAPER.
